Primary Examiner — Susan Bennett Hattan*Assistant Examiner* — Marie Fast Horse(74) *Attorney, Agent, or Firm* — Soquel Group LLC(57) **CLAIM**

The ornamental design for a curved light guide frame, substantially as shown and described.

DESCRIPTION

FIG. 1 is a perspective view from the front of a curved light guide frame, showing our new design;

FIG. 2 is a perspective view from the back thereof;

FIG. 3 is a top view thereof;

FIG. 4 is a bottom view thereof;

FIG. 5 is a left side view thereof, the mirror image of which is a right side view thereof;

FIG. 6 is a front view thereof; and,

FIG. 7 is a back view thereof.

The broken line showings of the remainder of light guide frame are for illustrative purposes only; the broken lines form no part of the claimed design.
